BLOOD SPECIMEN CONTAINER AND COOPERATING WITHDRAWING MEANS

Aaron Dolmatch, Newark, N. J.

Application February 3, 1945, Serial No. 576,069

4 Claims. (Cl. 128—220)

1

This invention relates to means for withdrawing from the body of a patient a specimen of blood or other body fluid and depositing the same in a separable container which may be conveniently transported to an examining laboratory.

The invention has for an object to provide a simple and inexpensive instrumentality for the above stated purposes which comprises a glass container, preferably in the form of a test tube, and a novel attachable means adapted in conjunction and cooperation therewith to provide a manipulatable suction syringe structure, including a hypodermic needle which may be inserted in a patient's body from which a blood or other body fluid specimen is desired to be withdrawn.

The invention has for another object to provide an instrumentality of the kind mentioned comprising two tubular glass members adapted to be loosely engaged telescopically, one of said members being the container and the other serving as a plunger, novel means being provided for separably joining said members in slideable and yet air-tight relation, the plunger member being open end to end, and said plunger member being provided at its external end with an air-tight coupling means for connecting a hypodermic needle element in operative relation thereto.

Other objects of this invention, not at this time more particularly enumerated, will be understood from the following detailed description of the same.

An illustrative embodiment of this invention is shown in the accompanying drawings, in which:

Fig. 1 is a side elevation of the novel instrumentality made according to this invention, the same being shown in its initial collapsed condition; Fig. 2 is a longitudinal sectional view of the same in said collapsed condition; Fig. 3 is a similar longitudinal sectional view showing the same as operatively extended for suction effect; Fig. 4 shows the container with its fluid specimen content detached from the plunger means and its fittings, said container being shown in corked or stoppered condition ready for transportation; and Fig. 5 is a fragmentary sectional view of a modified form of end cap for the plunger member.

Similar characters of reference are employed in the above described views to indicate corresponding parts.

Referring to the drawings, the combined container and suction syringe instrumentality according to this invention includes a container member 10 having a closed bottom and an open top, the same being made of glass, and preferably in the form of a test tube. Movably tele-

2

scope into said container member 10, through the open top end thereof, is a tubular plunger member 11, which is open at both its bottom and top ends, the same being also made of glass.

5 Due to the form and arrangement of the hereinafter described means for joining said telescopically related container and plunger members 10 and 11 in movable and yet air-tight relation, the latter need not be precisely fitted in air-tight slideable direct contact one with the other but may be loosely fitted one into the other, and consequently may economically comprise available or standard sizes of tubular glass.

The means for joining said container and plunger members in slideable but air-tight relation comprises a sleeve 12 of soft rubber or equivalent resilient material, suitably sized to engage externally over the top open end portion of the container member 10. At its upper end, said sleeve 12 is provided with an inwardly and laterally projecting guide and sealing flange 13 which is integral therewith. The inner or free peripheral marginal portion of said guide and sealing flange 13 makes a close air-tight embracing contact with the external surface of the plunger member 11, whereby to seal the space between the container and plunger member walls, while nevertheless permitting relative sliding movements of said members.

15 The outer or top end of the plunger member 11 is closed by an end cap which includes means for coupling a hypodermic needle element in operative connection with said plunger member 11. Said end cap consists in a unitary structure preferably made of soft rubber or equivalent resilient material, and comprises a cap body 14 to bridge and close the top end opening of said plunger member 11, said cap body having a dependent peripheral skirt 15 to engage externally over and around the upper end portion of said plunger member. Extending axially upward from the cap body 14 is a tubular neck portion 16, the same being provided at its upper or free end with an inwardly and laterally projecting coupling flange 17. Coupled to said cap neck portion 16 is a hypodermic needle 18, the same having a butt portion 19 provided with an external annular channel or groove 20. Said butt portion 19 is 20 adapted to be inserted in the bore of said cap neck portion 16 in such manner that the coupling flange 17 of the latter enters said channel or groove 20 of the butt portion 19 of said hypodermic needle, whereby to both hold said needle 25 in connected relation to the plunger end cap,

as well as to effect an air-tight joint or seal between these parts.

When assembled ready for use, the plunger member 11 is moved downwardly into the container member 10, whereby to initially collapse the suction syringe structure formed thereby (see Figs. 1 and 2). With the instrumentality in such initial condition, the operator may cause the hypodermic needle to penetrate a vein of the patient from whom a blood specimen e. g. is desired to be obtained. After the needle is in communication with a vein, the operator slides the container member 10 outwardly along the plunger member 11, thus creating a reduction of pressure within the interior of the assembly, thereby inducing a suction effect which quickly withdraws blood from the vein. The thus withdrawn blood flows through the endwise open plunger member 11, and thence into the container member 10, so as to deposit a specimen B within the latter.

After a specimen B is thus obtained and deposited within the container member 10, the latter is drawn out of the embrace of the joint sleeve 12, so as to be released therefrom, and thus detached from the plunger member 11 and its associated parts (see Fig. 4). The container member 10 being thus separated, its open end may be closed by insertion therein of a suitable cork or stopper C. The closed container member, with its contained blood specimen B, may now be conveniently transported to a laboratory for desired examination and report.

Instead of separating the container member 10 from the plunger member 11, whereby to employ the former alone as the transportable container, the container and plunger member may, after use in obtaining a blood specimen, be optionally permitted to remain assembled, and merely the hypodermic needle 18 be removed from the cap neck portion 16, so that, after the plunger member is again collapsed into the container member, the bore of said cap neck portion may be closed by a suitably sized cork or stopper, whereupon the assembly itself may serve as a transportable specimen container.

The container and plunger members being made of glass, can be easily and thoroughly cleansed for reuse, and all parts of the instrumentality may be readily sterilized both prior to reassembly thereof and thereafter, so that a safe and sanitary condition of the instrumentality may be assured prior to each use thereof.

In Fig. 5 is shown a modified form of end cap means which may be optionally for closing the outer end of the plunger member 11. This form of end cap is of the plug type, which is preferably also made of soft rubber or equivalent resilient material, and comprises a plug body 21 insertable in the outer open end of the plunger member 11. Said plug body 21 is provided with an axial bore 22. At the outer end of said bore is an internal annular flange or bead 23. The hypodermic needle may be separably attached to said modified cap means by inserting its butt portion 19 into the plug body bore 21 in such manner that the flange or bead 23 enters the channel or groove 20, whereby to both hold said needle in connected relation to the plug body, as well as to effect an air-tight joint or seal between these parts.

From the above it will be apparent that the instant invention provides a very efficient and convenient instrumentality for the stated purposes, and one which is of very simple construction, involving but four parts exclusive of the hy-

podermic needle, and these both of low cost and subject to quick and easy assembly into operative relation, especially in view of the fact that the tubular glass container and plunger members need not be precisely finished and fitted together. The plunger member and its associated parts may be interchangeably used with a number of container members, all of which contributes to the provision of a very convenient, economical and time saving instrumentality for the purposes mentioned.

Having now described my invention, I claim:

1. A suction syringe attachment for containers of test tube-like form comprising an endwise open tubular member of smaller external diameter than the internal diameter of a container which it is to serve, whereby to loosely fit into the latter in telescopic relation thereto, a soft rubber sleeve through which said tubular member slidably extends, said sleeve comprising a skirt portion having an integral inwardly projecting annular flange portion at its upper end to constrictively embrace said tubular member in air-tight sealing but nevertheless slidable relation thereto, while at the same time offsetting said skirt portion in outwardly spaced concentric relation to said tubular member, said skirt portion being adapted to be detachably engaged over the open end of a container so as to constrictively embrace the same in stationary air-tight sealing relation thereto, and means for attaching a hypodermic needle in operative communicating relation to the outer end of said tubular member.

2. A device of the character described comprising an inner hollow tubular member open at both ends thereof, a hypodermic needle secured to the upper end of said inner tube, an outer hollow tubular member open at its upper end to slidably receive therewithin the inner tube and closed at its lower end, a gasket member comprising a manually engageable soft rubber sleeve surrounding and constrictively gripping the outer aspect of the outer tube adjacent its upper end, said sleeve having an integral, inwardly directed annular extension at the upper end of the sleeve reaching across the top of the outer member towards and slidably surrounding and constrictively gripping the inner member.

3. A device as in claim 2, in which the inwardly directed annular extension is recessed at its underside to receive therewithin the upper end of the outer member.

4. A device as in claim 2, in which the annular extension has a short reversely reaching sleeve portion, spaced from and parallel to the sleeve gripping the outer tubular member, the reversely reaching sleeve gripping the inner aspect of the outer member.

AARON DOLMATCH.
